[57] CLAIM

The ornamental design for a flower pot cover, as shown and described.

DESCRIPTION

FIG. 1 is a perspective view of a flower pot cover showing our new design;

FIG. 2 is a reduced side elevational view thereof, sides being substantially identical;

FIG. 3 is a reduced top plan view thereof;

FIG. 4 is a reduced bottom plan view thereof;

FIG. 5 is a fragmentary enlarged top plan view thereof;

FIG. 6 is a fragmentary enlarged top plan view of a second embodiment of the design of FIG. 1, the only difference being the configuration of the edge;

FIG. 7 is a fragmentary enlarged top plan view of a third embodiment of the design of FIG. 1, the only difference being the configuration of the edge;

FIG. 8 is a fragmentary enlarged top plan view of a fourth embodiment of the design of FIG. 1, the only difference being the configuration of the edge.

The flower pot cover has no substantial thickness.
